UNITED STATES PATENT OFFICE

159,158

BLOUSE WITH A REVERSIBLE FRONT

Pauline A. Landert, St. Louis, Mo.

Application December 2, 1949, Serial No. 6,375

Term of patent 7 years

(Cl. D3—25)

To all whom it may concern:

Be it known that I, Pauline A. Landert, a citizen of the United States, residing at the city of St. Louis, State of Missouri, have invented a new, original, and ornamental Design for a Blouse With a Reversible Front, of which the following is a specification, reference being made to the accompanying drawing, forming a part thereof, in which

I claim:

The ornamental design for a blouse with a reversible front, substantially as shown.

PAULINE A. LANDERT.
